UNITED STATES PATENT OFFICE.

SAMUEL SHAFFER, JR., OF MILWAUKEE, WISCONSIN, ASSIGNOR TO CHAIN BELT COMPANY, OF MILWAUKEE, WISCONSIN, A CORPORATION OF WISCONSIN.

CONVEYING APPARATUS.

1,290,792.

Specification of Letters Patent.

Patented Jan. 7, 1919.

Application filed February 5, 1914. Serial No. 816,778.

To all whom it may concern:

Be it known that I, SAMUEL SHAFFER, Jr., a citizen of the United States, residing at Milwaukee, in the county of Milwaukee and 5 State of Wisconsin, have invented certain new and useful Improvements in Conveying Apparatus, of which the following is a specification.

My invention relates to conveying apparatus, and has been wrought out with especial reference to being used in connection with a concrete mixing machine for delivering the product thereof to the sidewalk, pavement, or other place, where it is to be used; but 15 while the invention is illustrated as embodied in apparatus such as indicated, it is not limited in its useful applications to such mechanism.

In the accompanying drawings—

20 Figure 1 is a side elevation of a conveying apparatus embodying my invention;

Fig. 2 is an end view of the apparatus;

Fig. 3 is a transverse vertical section taken on the line III—III of Fig. 1;

25 Fig. 4 is an elevation of the conveying bucket, the means for controlling the doors through which it is discharged, and the supporting carriage, the near side frame of the latter being removed;

30 Fig. 5 is a top plan view of one of the side frame pieces of the carriage that supports the conveying bucket;

Fig. 6 is a side elevation of the said frame piece;

35 Fig. 7 is a side elevation of the sliding contact piece that operates as a trip to discharge the bucket; and

Fig. 8 is an end view of the said contact piece.

40 Fig. 9 is a detail vertical sectional view through the horizontal shaft constituting a pivot for the boom, parts being broken away.

In the accompanying drawings, 2 indicates a portion of a concrete mixing machine, and 3, the upright framework located 45 near the discharge end thereof.

4 designates a bracket supported by the framework 3, in which is mounted a vertical pivot 5 that carries at its lower end bearings 6 for a horizontal pivot 7, on which is supported a boom 8, constituting the track or way along which the conveyer travels. This

boom consists preferably of a pair of channel bars 9, 9, suitably spaced apart, the flanges of the channel bars extending outward and constituting tracks for the wheels 10 of a carriage 11 from which is suspended a conveying bucket 12. When a trackway such as described, that is, a rigid, adjustable boom, is employed, I prefer to provide for 60 its support and vertical adjustment by the following means. A cable 13 is connected, by brackets 14, (not shown in Fig. 2) with the boom and extends, over a swiveled pulley 15, to a winding drum 16. The said pulley and drum are mounted in an upward extension 17 of the frame 3. The drum is secured to a shaft 18 provided with a hand wheel, by means of which the cable may be let off or wound up at pleasure.

70 The carriage 11 consists essentially of a pair of side frame pieces 19, 19, suitably connected by cross bolts, and carrying the axles on which are supported the wheels 10. Each of these frame pieces is provided with a 75 short inwardly extending rib 20 terminating in abutments 21, these parts being for a purpose presently to be described.

I prefer to impart motion to the carriage by means of an endless chain belt 22, which 80 is supported upon a driving sprocket wheel 23, mounted upon the pivot 7, and another sprocket wheel 24, supported at or near the outer end of the boom. This latter wheel is preferably adjustable in order to provide 85 for regulating the tension of the chain belt 22, being supported in a sliding frame 25, the position of which is controlled by an adjusting screw 26. If found desirable one or more intermediate supporting idler sprockets 27 may be employed for holding up the chain belt and preventing undesirable sagging thereof.

90 Secured to one of the links of the chain belt is a block or contact piece 28, arranged 95 to serve as the medium through which motion is transmitted from the chain belt to the carriage 11. This contact piece has a limited movement relative to the carriage, for which purpose I mount it upon the ways 100 formed by the ribs 20 and between the abutments 21. The length of the contact piece is less than the length of the ways, and it is recessed at its edges, as indicated at 29, so as

to engage with and slide along the ribs 20. From this construction it follows that when that strand of the chain belt to which the contact piece is connected moves outward, 5 that is, toward the free end of the boom, said piece slides along the ways 20 until it engages with the outer abutment 21, whereupon it communicates motion to the carriage and the conveyer bucket moves to the place 10 of discharge. When this has taken place, and the direction of the chain belt is reversed, the contact piece moves, relative to the carriage, leaving the front abutment and sliding along the ways until it engages the 15 rear abutment, when it imparts motion to the carriage, forcing it inward or toward the pivoted end of the boom. This loose connection between the belt 22 and the carriage is availed of for the purpose of controlling 20 the doors through which the bucket 12 is discharged.

30, 30 indicate hinged doors in the bottom of the bucket, arranged to open outwardly for discharging the load. To these doors 25 are connected links 31, and these in turn are connected with a lock link 32 pivoted to an arm 33 that extends outward from an axle 34 mounted in the carriage 11. There are a contact arm 35 and an operating handle 37 also connected with the axle 34. The relation of the pivots of the links to the axis of the axle 34 is such that when the arm 33 is moved into the position shown in full lines in Fig. 4, the doors are held securely closed by a toggle lock of the parts, but a slight rotative movement of the axle is sufficient to carry the parts from this position, so that the doors will open freely. The opening of the doors may be accomplished by means of the handle 37, in a machine such as indicated in the drawings where the places at which the bucket discharges are being constantly changed; or preferably by a slight reverse motion imparted to the chain belt 22, which causes the contact piece 28 to engage the arm 33 and move it sufficiently to break the toggle lock, the piece 28 being for this purpose provided with a striking face 55. I arrange 45 to close the doors automatically as the bucket is brought into position to receive its charge. For this purpose I have arranged a cam 38 (not shown in Fig. 2), supported by brackets 41 from the boom. 50 This cam has an inclined face 39 with which a contact roller 36 at the end of the arm 35 engages as the carriage approaches the inner end of its run. As the contact roller moves along this inclined face of the cam 55 the doors are gradually closed until the parts assume the position shown in full lines in Fig. 4. I prefer to provide the cam with a straight face 40 with which the contact roller remains in engagement so long as the 60 bucket is at the inner end of its travel.

The lock link 32 is provided with a hook 43 that is adapted to engage with a cross piece 44 of the carriage when the doors are open, as indicated in dotted lines in Fig. 4. The doors are thereby held supported 70 when in open position, and are prevented from swinging.

A stop 42 is provided at the inner end of the boom for arresting the carriage and preventing it running off its track. 75

In order to provide for laterally adjusting the boom I secure to the vertical pivot 5 a gear segment 45 with which engages suitable adjusting means, such as a hand operated worm 46. 80

The chain belt 22 may be driven by any suitable mechanism. When the invention is applied to a concrete mixing machine as shown, I prefer that arrangement of driving gear which I will now describe. 85

47 is a bevel wheel, mounted upon the horizontal pivot 7 and connected with the inner sprocket wheel 23, it being preferably cast therewith. With this wheel engages a pinion 48 mounted upon a vertical shaft 49 90 that passes through and has bearing in the vertical pivot 5 for the boom. At the upper end of the shaft 49 is a bevel gear 50 with which engage a pair of diametrically opposed drive gears 51. These are loose upon 95 the drive shaft 53, and one or the other of them may be connected at the pleasure of the operator with the gear 50, through clutch mechanism 52 controlled by a hand lever 54. Since these driving parts constitute no part of my invention they are not illustrated in detail, and are merely referred to that the method of operating that embodiment of my invention illustrated, may be apparent. 100

It will be seen by reference to the drawings, that the lower operating strand or run of the endless chain belt lies between the channel bars of the boom which operate to cover and protect it. It will of course be 110 understood that for many purposes any other flexible power-transmitting device, such as a cable, is the equivalent of the chain belt herein referred to and shown. 105

The method of operating my invention is 115 as follows: The conveying receptacle is loaded, the doors 30 thereof being closed and locked, and then the chain belt or equivalent power-transmitting means is started and, through the contact piece 28, moves 120 the bucket and its carriage along the supporting way until the point of discharge is reached. Here the bucket doors are opened, and its contents discharged, whereupon it may be immediately returned to 125 position for loading, the bucket doors standing open during such return movement, but being held suspended and against swinging by the hook 43 of the lock link. As the bucket and its supporting carriage ap- 130

proach the loading position, the contact arm 35 is engaged by the cam 38 which operates to gradually close and lock the doors.

What I claim is:

- 5 1. In a concrete distributing apparatus, the combination of a supporting way, a conveyer carriage movable along the said way and formed with side frame pieces spaced apart and having opposite, inwardly extending, guide ribs of limited extent, and abutments at the ends of the ribs, a driving cable for moving the conveyer carriage, and a contact piece secured to the cable and grooved at its edges to engage with the said ribs.
- 10 2. In a concrete distributing apparatus, the combination of a boom formed of a pair of parallel channel bars spaced apart and united, a conveyer carriage the wheels of which run on the tracks formed by the flanges of the channel bars, the carriage having a frame that extends upward between the channel bars and is formed with

opposite, inwardly extending, guide ribs and with abutments terminating the said ribs, an endless driving cable for moving the conveyer carriage, means for supporting the cable with its lower strand between the channel bars of the boom, a contact piece connected with that run of the driving cable that is between the channel bars and supported upon the said guide ribs, the length of the contact piece being less than the length of the guide ribs between the abutments, and the contact piece being provided with a downwardly extending operating projection, an openable, discharging bucket carried by the conveyer carriage, and means controlling the opening and discharge of the said bucket arranged to be operated by the operating projection of the contact piece.
